BUILDING CONSTRUCTION

Don William Wells, El Centro, Calif.

Application May 23, 1934, Serial No. 727,092

16 Claims. (Cl. 72—70)

This invention relates to building construction, and one of the objects of the invention is to provide simple means for forming the walls and floors of buildings of cementitious material, without the necessity for forming rigid molds for the cementitious material.

A further object of the invention is to provide a frame of simple construction, which can be manufactured at low cost, and which can be readily employed for attachment to a reticulated sheet material and lathing material; also to accomplish this without the necessity for employing special tools; or highly skilled mechanics.

A further object of the invention is to provide a frame member such as referred to above, to be used as an element in wall and floor construction, and which is so constructed as to facilitate its attachment to a reticulated sheet material, which is to be embedded in a cementitious material, to construct said frame members in such a way that they can be readily secured to the reticulated sheet material, and to provide for attaching a lathing material.

A further object of the invention is to provide a building construction, which can be readily employed for forming hollow walls of cementitious material, and easily insulated, outside or inside, or through the whole thickness of wall.

A further object of the invention is to provide simple means for setting up a skeleton wall of metal, enabling a cementitious material to be readily applied to the skeleton to form an outer wall integral with columns or studs, and without necessity for employing rigid walls for the pouring of cementitious material.

A further object of the invention is to provide a simple metallic skeleton to facilitate the formation of floors of cementitious material with beams below the same.

A further object of the invention is to provide a simple skeleton construction to be employed in forming a building wall, and to construct the same in such a way as to minimize the conducting of heat through the wall.

A further object of the invention is to provide an improved wall construction, particularly adapted to forming light partition walls.

Another object of the invention is to provide a simple construction of the type referred to above, and which will result in producing substantially fireproof building construction.

A further object of the invention is to provide a fireproof construction, made up of simple members that require no special shop work for erection.

Further objects of the invention will appear hereinafter.

The invention consists in the novel parts and combination of parts to be described hereinafter, all of which contribute to produce an efficient building construction.

A preferred embodiment of the invention is described in the following specification, while the broad scope of the invention is pointed out in the appended claims.

In the drawings:

Fig. 1 is a horizontal section taken through a skeleton construction set up for forming a wall and stud, and indicating means for facilitating the attachment of metal lathing to the inner side of the wall for receiving plaster.

Fig. 2 is a perspective of a frame member, which I prefer to employ as an element in constructing the walls and floors of the building embodying my invention.

Fig. 3 is a perspective showing a section of a wall constructed in accordance with my invention, but before the cementitious material has been applied to the skeleton frame.

Fig. 4 is a horizontal section corresponding to Fig. 1, but showing the wall complete with the cementitious material applied to form the outer panel of the wall and a stud. This view also illustrates plaster applied to metal lathing at the inner side of the wall.

Fig. 5 is a view similar to Fig. 4, but illustrating an embodiment of the construction in which insulating material may be poured in the wall space between the plaster and the exterior panel of the wall to form an insulated building capable of greatly reducing the passage of heat through the wall.

Fig. 6 is a vertical section through a wall at a column or stud, and also passing through a floor at a beam.

Fig. 7 is a horizontal section illustrating how my invention adapts itself for forming a wall intersection at the corner of a building.

Fig. 8 is a vertical section taken on the line 8—8 of Fig. 6, and passing through a portion of a floor and through a floor beam.

Fig. 9 is a horizontal section illustrating the adaptation of my invention to the formation of a light wall construction such as employed in forming partition walls. This view also illustrates a construction involving the use of a spacer for giving rigidity to a light partition wall.

Fig. 10 is a perspective further illustrating the construction of a partition wall illustrated in Fig. 9, and particularly illustrating the spacer

referred to in the manner of employing the same.

Referring more particularly to the parts, and especially to Figs. 1 to 4, in practicing my invention I provide a plurality of frame members, or frames 1, and these frames are preferably in the form of A-frames with two arms 2, which are formed by bending strap metal to form an angle or apex 3. The ends of the legs are formed with hooks 4 of bifurcated form, and between the hooks the metal is stamped inwardly to provide integral means for engaging cooperating members in the wall or floor construction. This means is preferably in the form of a tongue 5 stamped inwardly. In this way, the hooks 4 would be of bifurcated form. I also prefer to provide means integral with the arms for engaging wires extending transversely to the plane of the frames 1, for a purpose which will appear hereinafter. This means consists of two small fingers 6, which are struck from the inner edges of the sockets 7 that are formed between the individual hooks 4a that form the bifurcated hooks 4. These fingers 6 are preferably bent inwardly at the sockets, (see Fig. 2).

Adjacent the angle or apex 3, I provide means for securing each A-frame to a stringer extending transversely to the plane of the frames to connect them, and this means, if desired, may be integral with the frames for securing lathing material for forming the plaster side of the wall, or for forming a plaster ceiling. This means may consist of two tongues 8 and 9, which if desired may be struck from the material and pressed outwardly in some such manner as illustrated in Fig. 2. It is not essential to have these parts integral with the frames. In this way, two oppositely disposed tongues 8 are formed projecting from the angle 3, and two oppositely disposed tongues 9 are formed projecting in a similar manner.

On the sides of the arms 2 and near the apex if desired, integral tongues 10 can be struck outwardly from the material to form seats for insulating boards, as will be described in connection with Fig. 1, and also if desired at this point, long tongues 11 may be struck inwardly, to extend into the interior of the cement stud, molded or poured into the space surrounded by the A-frames. These frames 1 constitute an important element in the construction of walls and floors in practicing my invention.

Referring now to Figs. 3 and 6, in forming a wall, I set up a reticulated sheet material 11, and this sheet material is preferably of 2" wire mesh in ordinary wall construction, comprising equidistant horizontal bars or wires 12, and equidistant vertical bars or wires indicated generally by the numeral 13. These bars are usually welded together at their intersections when the material is received from the factory. This material is usually supplied in rolls, and the material can be taken from the rolls as desired.

Having set up the reticulated sheet material 11, I attach a plurality of A-frames 1 in vertical alignment, by hooking the hooks 4a onto two of the vertical rods 13, the same being indicated specifically by the numerals 15 (see Fig. 1). Adjacent to the ends of the arms 2, and preferably located in the sockets 7, I provide horizontal runners 14, which are preferably of angle-form with the flanges of the angle projecting outwardly toward the wire mesh 11, and the edges of these flanges seat against the inner sides of the vertical wires 13 of the mesh. I

then bend down the tongues 5 as indicated in Fig. 1, so that their ends are jammed against the outer edges or angle of each runner. In doing this, the tongues 5 can be slightly bowed so that their resilience assists in retaining them in their tight condition.

At the angles 3 of the A-frames which lie adjacent the inner side of the wall, I provide a metal stringer 19, which is of saddle-form, presenting diverging flanges that lie over the arms 10 2 adjacent the angle 3. These stringers extend vertically throughout the height of the wall, and connect the A-frames. After they are put in position, they are secured by any suitable means. In the present drawings this is accomplished by bending the tongues or fingers 9 down over their outer sides as indicated in Fig. 1. This leaves the fingers or tongues 8 still projecting outwardly, and these fingers are utilized to secure metal lathing material 20, indicated by the dotted lines 20 in Fig. 1. In this way, I form a hollow wall skeleton with molding spaces 21 to form studs. I then apply sheeting 16 along the inner sides of the runners 14, so that this sheeting is spaced from the plane of the wire mesh 11. This sheeting is carried inwardly from the outer side of the wall so as to pass over the outer faces of the stringers 19 and envelop the aligned A-frames. This sheeting may be of any suitable continuous material, such as tar paper, or any other suitable material. In order to secure this sheeting neatly on the aligned A-frame, I provide vertical wires 17 that pass through the eyes 18 that are formed by the bent fingers 6 between their bights and the outer faces of the arms 2, (see Fig. 1). The fingers 6 should be bent down around these wires. These wires hold the outer portions of the web or sheeting 16 flat against the arms 2. If desired, horizontal runners 22 may be provided, consisting of 40 horizontal angle bars running horizontally. In the present instance they are illustrated as running inside of the vertical stringers 19; and if desired, vertical reinforcing bars 23 and 24 may be provided and tied in position with light wire 45 ties 25. If it is desired to insulate the wall, this can be accomplished by providing panels 26 of insulating material laid on the projecting tongues 10, which form seats for the same.

Now the wall is ready to be poured or "shot" 50 with a cement gun. In doing this, the cement is shot against the sheeting 16 until the wire mesh 13 is embedded, and as the wall is built up, the cement is shot into the molding space 21 to form a stud 27, which will be integral with 55 the outer section 28 of the wall. Stucco (not illustrated), can be applied to the outer face of the wall. Any suitable cementitious material may be applied for forming the outer wall section 28 and the studs 27. As the cementitious material is shot into the stud space, the sheeting material covering the outer sides of the arms, will be bulged outwardly as indicated at 60 29, in Fig. 4. This is advantageous because it enables the cementitious material to extend 65 around to the outer sides of the arms 2, as indicated at 30 in Fig. 4. This embeds the frames and fireproofs the studs. If the studs are deep or high, it may be necessary to brace the side 70 faces of the web or sheeting by putting in intermediately located brace wires 17a. These wires will back up the web and enable the web to hold the cement or concrete if the studs are poured. If the studs are poured the wall be- 75

tween the studs can be "shot" or hand-plastered as may be desired.

The tongues 5, of course, increase the anchoring effect of the A-frames in the studs, but if desired to increase the anchoring effect, this can be accomplished by bending the tongues 11 inwardly as indicated in Fig. 1, so that they too, are embedded in the cement.

In the construction of very light walls where it is necessary to provide for bracing the inner and outer sections of the wall without necessitating the use of studding at all points where the A-frames are aligned, I may blank out some of the studs by laying a shield back of the runners 14, as indicated by the dotted line 31 in Fig. 1. This shield can be made of sheeting like the web 16, or a board 31a indicated in dotted lines in Fig. 1, may be set up to close the outer side of the skeleton stud to retain poured concrete, and the walls hand-plastered.

In case it is desired to employ a molded insulating material instead of previously molded panels of this material, I may provide for accomplishing this in the manner indicated in Fig. 5. In doing this, I run a second web 32 of sheeting material over the angles of the studs, as indicated in Fig. 5, and provide wires 33 held in place by integral fingers 34 on the arms 2a (see Fig. 5), for holding this outer web 32 in position. This web can be placed at a considerable distance from the metal lathing 34 so as to form a molding space into which the insulating material 35 can be poured.

Substantially the same procedure is employed using my A-frames for forming floors and ceilings. This is illustrated in Fig. 8, in which 37 indicates 2" wire mesh supported about the floor level. The A-frames 38 are hung downwardly on their hooks 39 in longitudinal alignment and their lower ends are connected by a stringer 40, which is secured to the A-frames by integral fingers or tongues similar to the tongues or fingers 8 and 9, as described in connection with Fig. 4. Horizontal wires 41 are strung along the outer sides of the arms of the A-frames, like the wires 17. This enables webbing or sheeting 42 to be run along under the wire mesh and spaced sufficiently below the same to enable the cement floor 43 to be shot or laid over the sheeting 42, and this sheeting extends under the frames enabling beams to be formed integral with the floors. This beam should have a reinforcing rod 44 laid in its lower portion as a tension member, and if desired, an upper reinforcing rod 45 may be provided, but this is not essential in a beam construction. At the stringers 40, metal lath 46 is attached in the manner illustrated in connection with Fig. 4, and this metal lath 46 will support plaster 47 for the ceiling.

In placing the cement to form the beam 43, the cement will bulge the webbing 42 along the sides of the arms, so as to flow under the arms of the frames 38, and embed them in the cement, forming a fireproof structure.

In Fig. 6, I illustrate a beam intersecting with the stud 27. There is no difficulty about forming this intersection. It is preferable to provide an A-frame 48 in the stud at about the level of the plaster 49 that extends under the lower edge of the beam at the ceiling wire lath 50. It is also preferable to provide a similar A-frame 49 in a vertical plane, aligning with the other A-frames that form the beam.

The webbing that extends into the intersection from the stud and from the beam, is preferably

cut so that the two webs meet each other and overlap on an inclined line 50.

If it is necessary to carry the wall above the floor 51, the upper wall is tied to the beams and the lower wall, by permitting the ends of the stringers 52 to extend up above the floor level. These stringers 52 correspond to the stringers 9. It is also advisable to extend the reinforcing 53 corresponding to the reinforcing bar 23 illustrated in Fig. 1. These parts 52 and 53 facilitate making a good anchorage for the upper wall.

In forming an intersection or corner for two walls, this is preferably accomplished as indicated in Fig. 7. In doing this, I provide a plurality of vertically aligned A-frames 54 at each side of the corner 55. The webbing 56 is supported in a vertical plane back of the wire mesh 57, and is run up along the outer sides of the A-frames remote from the corner 55, the end of the web being secured under vertical stringers 58 corresponding to the stringers 19 and secured in place in the same manner as illustrated in Fig. 3. The wire mesh 57 extends out on both intersecting walls to the corner 55.

Horizontal runners 59 extend along the inner sides of the frames. The plaster 60 on the inner sides of the walls can be applied first, against metal lath 61, and if desired, a vertical angle stringer 62 can be run in the inside corner 63. The cement for forming the outer section 64 of the wall, is shot against the webbing 56, and fills the space surrounded by the A-frames 54, and also fills the space between these A-frames so as to form a solid cement corner 65.

In Figs. 9 and 10, I illustrate the use of my invention in forming a light partition wall 66. This wall is shown in horizontal section in Fig. 9. I provide a plurality of A-frames 67 in vertical alignment, and spaced apart to form light studs. These vertically aligned A-frames are connected by vertical stringers 19a at their angles, and by vertical stringers 19b at their hooks 4c, and by horizontal runners 68 of angle metal inside of the stringers. They are tied to the A-frames in any suitable manner such as described herein, and metal lath 69 is set up on each face of this skeleton frame. To this metal lath 69, plaster 70 is applied. If this partition must carry a load, it should have a web run on each side of it like the web 16, and have concrete poured into it. In this construction, where the partition is not supporting any load, the skeleton studs formed of vertical aligned A-frames 67, may be spaced a considerable distance apart, in which case I provide strut braces 71 such as the brace 71, located between the runners 68 and midway between the skeleton columns or studs. Each of these braces 71 consists of an elongated plate having a notch 72 at each end, to receive an angle 73 of the adjacent runner. In the ends of the braces 71, vertical angle stringers 74 are placed, and these are tied to the outer sides of the runners 68 by integral fingers 75, on the ends of the braces, which are bent around the outer sides of the vertical stringers, as illustrated in Fig. 10.

Referring again to Fig. 4, if desired, a plurality of runners such as the runner 76, may be provided for tying the inner ends of the A-frames together horizontally. In this instance the runner is located just inside of the vertical stringer 19, and may be tied to the stringer in any suitable manner.

It will be evident that in accordance with my invention, a building can be constructed in a

very simple manner, and without employing special tools, enabling skeleton walls and skeleton floors to be readily set up, which can be shot with cementitious material to form a substantial building construction.

A building constructed in accordance with my invention, is very readily insulated. In this connection, it will be noted that all heat passing in or out through the wall, must pass through the vertical stringers 19, and these stringers themselves, are completely embedded in the stucco or plaster applied to the inner side of the skeleton wall. My invention enables substantially fireproof reinforced cement buildings to be erected at a relatively low cost.

The skeleton wall is so light that in practice, an entire side wall, or a section of it may be set up in a factory and then moved out and set up on the foundation of the house to be erected. This would effect a considerable saving in labor cost. If it is desired to ship the A-frames to distant points they should merely have their tongues and integral fingers cut out, but left in the plane of the side bars. This enables them to be nested for shipment in compact form.

It is understood that the embodiment of the invention described herein, is only one of the many embodiments this invention may take, and I do not wish to be limited in the practice of the invention, nor in the claims, to the particular embodiment set forth.

What I claim is:—

1. In a building construction, the combination of a reticulated sheet material, a plurality of aligned frames, each frame having a pair of arms with means formed integrally on their ends for engaging into the reticulated sheet material, a sheeting material covering the inner side of the reticulated sheet material and extending along the sides of said arms so as to envelop the outer sides of the same, a stringer extending past said frames and located remote from the reticulated material, means for tying the stringer to the said frames, and for attaching sheet lathing material at the inner side of said stringer.

2. In a building construction, the combination of a reticulated sheet material having a plurality of substantially parallel bars, a plurality of frames, each frame having a pair of arms with means formed integrally on their ends for engaging a pair of said bars, a sheeting material covering the inner side of the reticulated sheet material and extending along the sides of said arms so as to envelop the outer sides of the same, a stringer extending longitudinally with the said bars and located remote from the reticulated material, means for tying the stringer to the said frames, sheet lathing material attached at the inner side of said stringer, a runner extending transversely to the said bars on the sides of the bars remote from the hooks, and means formed integrally on said arms capable of being moved into a position to force said runners against said bars to secure the A-frames to the said bars.

3. In a building construction, the combination of a reticulated sheet material having a plurality of substantially parallel bars, a plurality of frames, each frame having a pair of diverging arms with hooks formed integrally adjacent their ends to be hooked onto a pair of said bars, a sheeting material covering the inner side of the reticulated sheet material and extending along the sides of said arms so as to envelop the outer sides of the said frames, a stringer of saddle-form extending substantially parallel to

the said bars, connecting the ends of said frames remote from the said bars, a sheet lathing material disposed against the side of the said stringer remote from the frames, means formed integral with the frames for tying the stringer to the frames and for tying the said lathing material to the stringer, a plurality of runners disposed against the inner faces of the said bars, said frames having integral means capable of being jammed against the sides of the runners remote from the bars so as to hold the runners against the bars and lock the hooks to the reticulated sheet material.

4. In a building construction, the combination of a reticulated sheet material having a plurality of substantially parallel bars, a plurality of A-frames, each A-frame having a pair of arms with hooks formed on their ends for engaging a pair of said bars, a sheet material extending along adjacent the inner face of the reticulated sheet material but spaced therefrom, said sheet material extending along the sides of said arms so as to envelop the outer sides of the A-frames, a stringer extending longitudinally with said bars of the reticulated material and located remote from the reticulated material, means formed integral with the said A-frames for tying the stringers to the A-frames, and means for attaching sheet lathing material at the inner side of said stringer.

5. In a building construction, the combination of a reticulated sheet material having a plurality of substantially parallel bars, a plurality of A-frames, each A-frame having a pair of arms with hooks formed on their ends for engaging a pair of said bars, a sheet material extending along adjacent the inner face of the reticulated sheet material but spaced therefrom, said sheet material extending along the sides of said arms so as to envelop the outer sides of the A-frames, a stringer extending longitudinally with said bars of the reticulated material and located remote from the reticulated material, means formed integral with the said A-frames for tying the stringers to the A-frames, means for attaching sheet lathing material at the inner side of said stringer, a runner extending transversely to the said bars on the sides of the bars remote from the hooks, and means formed integrally on said arms capable of being moved into a position to force said runners against said bars to secure the A-frames to the said bars.

6. In a building construction, the combination of a reticulated sheet material having a plurality of substantially parallel bars, a plurality of A-frames, each A-frame having a pair of arms with hooks formed on their ends for engaging a pair of said bars, a sheet material extending along adjacent the inner face of the reticulated sheet material but spaced therefrom, said sheet material extending along the sides of said arms so as to envelop the outer sides of the A-frames, a stringer extending longitudinally with said bars of the reticulated material and located remote from the reticulated material, means formed integral with the said A-frames for tying the stringers to the A-frames, means for attaching sheet lathing material at the inner side of said stringer, a runner extending transversely to the said bars on the sides of the bars remote from the hooks, means formed integrally on said arms capable of being moved into a position to force said runners against said bars to secure the A-frames to the said bars, the ends of said arms at

said hooks having sockets formed therein to receive the said runners.

7. In a building construction, the combination of a reticulated sheet material having a plurality of substantially parallel bars, a plurality of A-frames, each A-frame having a pair of arms with hooks formed on their ends for engaging a pair of said bars, a sheet material extending along adjacent the inner face of the reticulated sheet material but spaced therefrom, said sheet material extending along the sides of said arms so as to envelop the outer sides of the A-frames, a stringer extending longitudinally with said bars of the reticulated material and located remote from the reticulated material, means formed integral with the said A-frames for tying the stringers to the A-frames, means for attaching sheet lathing material at the inner side of said stringer, a runner extending transversely to the said bars on the sides of the bars remote from the hooks, means formed integrally on said arms capable of being moved into a position to force said runners against said bars to secure the A-frames to the said bars, said arms having integral means struck from the same adjacent the stringer but spaced therefrom for forming seats for insulating material, and an insulating material located in the space between said seats and said stringer.

8. In a building construction, the combination of a reticulated sheet material, a plurality of aligned A-frames, the A-frame having a pair of arms with hooks formed on their ends to be hooked into the reticulated sheet material, a sheeting material covering the said A-frames and extending substantially parallel with the reticulated sheet material, a pair of wires extending transversely to the aligned A-frames and attached thereto adjacent the reticulated sheet material for holding the said sheeting on the A-frames and for holding a portion of the sheeting spaced from the said reticulated sheet, a second piece of sheeting covering the ends of the A-frames remote from the reticulated material and extending from the A-frames substantially parallel with the reticulated material, another pair of wires connecting the said A-frames at an intermediate point on said arms for holding a second-named sheeting on the A-frames, means for securing said second-named wires to the A-frames, metal lath substantially parallel with the reticulated sheet material and disposed adjacent the ends of the A-frames remote from the reticulated sheet material, a cementitious material embedding the said reticulated sheet material and extending into the interiors of the A-frames, and a molded insulating material received in the space between the said second sheeting and the metal lath.

9. In a building construction, the combination of a reticulated sheet material having a plurality of substantially parallel bars, a plurality of aligned A-frames, each A-frame having a pair of arms with hooks formed on their ends to be hooked onto the sides of the said bars with the A-frames extending from the reticulated material on the side opposite to said hooks, a pair of wires on the outer sides of the arms of the A-frames and connecting the said A-frames, with means for securing the said wires to the arms of the A-frames, a sheeting material extending substantially parallel with the reticulated sheet material passing under the said wires and covering the outer sides of the said A-frames, a stringer extending transversely to the A-frames and connecting the ends remote from the reticulated sheet

material, means for securing the stringer to said A-frames, a lath material, with means for securing the same to the stringer, and a cementitious material embedding the said reticulated sheet material and extending into the space enclosed by the said A-frames to form a stud or beam.

10. In a building construction, the combination of a reticulated sheet material having a plurality of substantially parallel bars, a plurality of aligned A-frames, each A-frame having a pair of arms with hooks formed on their ends to be hooked onto the sides of the said bars with the A-frames extending from the reticulated material on the side opposite to said hooks, a pair of wires on the outer sides of the arms of the A-frames and connecting the said A-frames, with means for securing the said wires to the arms of the A-frames, a sheeting material extending substantially parallel with the reticulated sheet material passing under the said wires and covering the outer sides of the said A-frames, a lath material, with means for securing the same to the inner ends of the A-frames, and a cementitious material embedding the said reticulated sheet material and extending into the space enclosed by the said A-frames to form a stud or beam, the ends of said arms adjacent said hooks having sockets formed therein, and a runner corresponding to each A-frame, received in said sockets extending transversely to said bars and lying adjacent the inner face of the reticulated sheet material.

11. In a building construction, the combination of a reticulated sheet material having a plurality of substantially parallel bars, a plurality of aligned A-frames, each A-frame having a pair of arms with hooks formed on their ends to be hooked onto the sides of the said bars with the A-frames extending from the reticulated material on the side opposite to said hooks, a pair of wires on the outer sides of the arms of the A-frames and connecting the said A-frames, with means for securing the said wires to the arms of the A-frames, a sheeting material extending substantially parallel with reticulated sheet material passing under the said wires and covering the outer sides of the said A-frames, a lath material, with means for securing the same to the A-frames, a cementitious material embedding the said reticulated sheet material and extending into the space enclosed by the said A-frames to form a stud or beam, the ends of said arms adjacent said hooks having sockets formed therein, a runner corresponding to each A-frame, received in said sockets extending transversely to said bars and lying adjacent the inner face of the reticulated sheet material, and means integral with said arms capable of being forced against the inner sides of the runners to press the same against the inner faces of said bars and secure the hooks to the reticulated sheet material.

12. In a wall construction for a building, the combination of a substantially vertical reticulated sheet material having a plurality of substantially vertical bars, a plurality of aligned A-frames having arms with hooks on their ends to be hooked to the vertical bars, horizontal runners corresponding to the arms and connecting the same, said arms having integral means to be bent against the runners opposite the hooks to secure the A-frames to the said vertical bars, a vertical stringer corresponding to the aligned A-frames and connecting the same at their ends remote from the reticulated sheet material, metal lathing, means for securing the same to the ver-

- tical stringer, sheeting extending substantially parallel with the reticulated material enveloping the outer sides of the said A-frames and operating to form a stud molding space for a stud within 5 in and connecting the A-frames, said sheeting being spaced away from said reticulated material to enable a wall of cementitious material to be formed on the reticulated material with an integral stud in the stud molding space.
10. 13. In a building construction, a frame member having a pair of connected arms with hooks on the ends of said arms, and having sockets in their ends adjacent said hooks to receive a cross bar, the ends of said arms remote from said 15 hooks having tongues struck from the same for securing metal lathing to the inner ends of said frame members.
14. In a floor construction for a building, the combination of a substantially horizontal reticulated sheet material, a plurality of aligned 20 beam-frames, each beam frame having a pair of arms with hooks on their ends to be hooded into the reticulated sheet material, sheeting extending substantially horizontally and spaced below the reticulated sheet material, said sheeting extending 25 along the under sides of the said beam-frames, wires extending substantially horizontally below the reticulated material and connecting the said beam-frames for supporting the said sheeting, a stringer connecting the lower ends of the beam-frames and secured to the same, and

lath material secured to the under side of said stringer, said beam-frames and said sheeting co-operating to form a molding space for a floor of cementitious material extending down into the space surrounded by said beam-frames to form a 5 floor-beam.

15. In a wall construction, the combination of a plurality of frames spaced apart and at substantially the same level, each of said frames having a pair of arms disposed in a substantially 10 horizontal plane, a horizontal runner connecting the outer ends of said arms, horizontal runners connecting the other ends of said frames and spaced from the first-named runners, substantially vertical bars on the outer sides of said 15 runners and located between the frames, and a spacer extending substantially at right angles to the plane of the wall, said spacer having a socket in each end to receive one of the said runners, and having integral tongues bent around the 20 outer sides of said vertical bars.

16. In a building construction, a frame member having a pair of connected arms forming an acute angle with each other, with hooks on the ends of said arms, and having sockets in their ends 25 adjacent said hooks to receive a cross bar, the ends of said arms remote from said hooks having tongues struck from the same for securing metal lathing to the inner ends of said frame members.

DON WILLIAM WELLS. 30
